ENDLESS TREAD MACHINE

Benjamin H. Flynn, Alexandria, La.

Application February 17, 1936, Serial No. 64,392

4 Claims. (Cl. 305—4)

The invention relates to endless tread supporting means for mobile machines, and it is intended primarily for heavy machines used in highway construction, for instance, subgraders. It has heretofore been the practice to provide such machines with flanged wheels to travel upon the usual side forms used in the construction of concrete highways, but due to the weight of the machines, the wheels often severely injure said side forms, making frequent and expensive replacements necessary. One of the foremost objects of the present invention is to provide novel endless tread supporting means for the heavy machines to so distribute the weight upon the side forms as to prevent injury thereto.

A further object is to provide a new and improved endless tread supporting means (whether operating upon side forms or rails or upon the ground) in which the weight of the machine is supported upon the entire lengths of the lower reaches of the endless tread chains and in which the chains and tracks are engaged in a novel manner.

A still further object is to provide an improved construction in which no sprockets are necessary for mounting endless tread chains which support one end of the machine, and in which the sprockets necessary for driving endless chains which support the other end of the machine, are the only sprockets required in mounting these chains.

Still another object is to provide a novel construction in which the endless tread chains may be conveniently formed by merely fastening tread plates to the links of conventional heavy-duty roller-type sprocket chains, said tread plates being flanged if intended to travel upon side forms or rails.

With the foregoing and minor objects in view, the invention resides in the novel subject matter hereinafter described and claimed, description being accomplished by reference to the accompanying drawings.

Fig. 1 is a side elevation partly broken away and in section showing a subgrader improved in accordance with the present invention.

Fig. 2 is an enlarged detail horizontal sectional view on line 2—2 of Fig. 1.

Fig. 3 is a detail vertical longitudinal sectional view on line 3—3 of Fig. 2.

Fig. 4 is a detail vertical transverse sectional view on line 4—4 of Fig. 1.

Fig. 5 is an enlarged detail horizontal sectional view on line 5—5 of Fig. 1.

Fig. 6 is an enlarged transverse sectional view on line 6—6 of Fig. 1.

Fig. 7 is a vertical sectional view on line 7—7 of Fig. 1.

Fig. 8 is a detail horizontal sectional view on line 8—8 of Fig. 7.

While the construction illustrated in the drawings may be considered as preferred and will be rather specifically described, it is to be understood that within the scope of the invention as claimed, numerous variations may be made. Moreover, while a subgrader has been shown embodying the invention, it will be understood that the latter is not restricted to use with any particular kind of machine.

The subgrader G includes a motor-driven cutting drum D provided with appropriate means A whereby its ends may be independently or simultaneously adjusted between the side forms F upon which the machine travels.

Two endless tread chains 10 are provided for the front of the machine and two similar chains 10^a are provided for the rear thereof, and provision is made whereby the weight of the machine is supported upon the entire lengths of the lower reaches of these chains and whereby the front of the machine may be raised or lowered with respect to the chains and the side forms without disturbing the distribution of weight upon the lower reaches of said chains.

The endless tread chains 10 and 10^a are preferably formed by riveting or bolting flat tread plates 11 to lugs 12 now commonly provided on the side links 13 of conventional heavy-duty roller-type sprocket chains. Such chains, in addition to the side links 13 include central links 14, the rollers 15 being mounted upon transverse axes between said side and central links, this being explained in view of the fact that the links and rollers are associated in a novel way with certain track construction to be hereinafter described.

The means for supporting the front end of the machine upon the lower reaches of the chains 10, includes tracks 16 circumscribed by said chains 10 and engaging all of the rollers thereof, together with suitable jacks 17 connected with said tracks and the frame of the machine for vertically adjusting the front end of the latter. The means for supporting the rear end of the machine upon the lower reaches of the rear chains 10^a, includes driven sprockets 18 and tracks 19. While there is one track 16, one track 19, one jack 17 and one sprocket 18 at each side of the machine, these parts have been shown for one side only to avoid duplication of illustration. The track 16 is provided with a continuous edge 20.

preferably straight along its upper and lower portions and curved at the front and rear ends of said track, these curved portions occupying the bight portions of the chain 10. For purposes of adjustment to compensate for wear, one end 5 of the track 16 may be separate from the remainder of said track and adjustably connected to it by any preferred means 22. To the central portion of the track 16, the arched lower end 10 of the jack 17 is pivoted as shown at 24, the pivot preferably passing through a sleeve 25 which extends through said track and is welded to the latter. The upper portion of the jack 17, connected with the frame of the machine G 15 is preferably constructed as seen in Fig. 7. A vertical screw 26 is welded or otherwise secured to the arched portion 23, the upper end of this screw having threaded engagement with a sleeve 27 which is rotatably mounted on the frame of the machine as shown at 28, this sleeve being provided with a lock nut 27a. The portion of the screw 26 below the sleeve 27 is preferably provided with a surrounding tube 29 welded or otherwise secured thereto and resting upon the arched 20 portion 23 to which it may also be fastened. This tube 29 is slidably received in a fixed tubular guide 30 welded or otherwise secured to the machine frame. By rotating the sleeve 27 with a wrench or the like, the front end of the machine 30 is vertically adjusted as may be required.

The jack 17, the track 16 and the chain 10 are preferably located between inner and outer side plates 31 and 32 embodied in the construction of the machine frame, and the sprocket 18, track 35 19 and chain 10a are also preferably housed between these plates. The hub 33 of the sprocket 18 is rotatable on a stub-shaft 34 passing through suitable openings in and secured to the plates 31 and 32, said hub being provided with a driving sprocket 35 engaged by chain 36 forming a portion of appropriate driving mechanism 37 for said sprocket 18, all of this driving mechanism being housed between the plates 31 and 32.

The track 19 is of such shape and length as 45 to engage substantially all of the rollers of the chain 10a which are not engaged by the sprocket 18, and said track is provided with radius plates 38 which are welded or otherwise secured thereto, said radius plates having openings 39 50 through which the hub 33 of the sprocket 18 passes. A short rod or the like 40 is secured to the track 19 and passes through openings in said track and the radius plates 38, the ends of said rod or the like being received in short vertical 55 slots 41 formed in the plates 31 and 32. Adjusting screws or the like 42 are carried by these plates and may be turned down to rest solidly upon the rod or the like 40, even when the frame of the machine is tilted by operating the jacks 14. 60 Obviously, the frame will tilt about the shaft 34 as a pivot and during such tilting, the adjusting screws 42 will rise from the rod or the like 40 so that momentarily the track 19 imparts less of the machine weight to the tread chain 10a 65 than it should. As soon as the adjusting screws 42 are tightened, however, this is overcome. Before again lowering the front end of the machine, the screws 42 should of course be loosened, but after lowering to the required extent, said 70 screws should again be snugly tightened.

When the machine is intended to be operated upon side forms or rails, the tread plates 11 of the chains 10 and 10a will be provided with flanges 43 to engage vertical faces of said side forms 75 or rails, to guide the chains along the latter.

If the machine be intended to merely operate upon the ground, the flanges 43 will not be required and the tread plates 11, being then subjected to greater wear, could well be of heavier construction to resist such wear.

From the foregoing, taken in connection with the accompanying drawings, it will be seen that I have provided a novel construction by which the weight of the machine is distributed over relatively large areas of the supporting surface or 10 surfaces instead of being localized or concentrated as when using supporting wheels. Moreover, the construction is such that the entire lengths of the lower reaches of the tread chains are utilized to support the weight of the machine without 15 placing any severe tensional strains upon said reaches, such as those which necessarily exist when uneven portions of the supporting surface thrust upwardly on portions of the chains not solidly held by contact with tracks or the like, for 20 instance, the chain portions ordinarily traveling across gaps between front and rear sprockets and chain-engaging tracks extending between the lower portions of said sprockets, as in a number of prior endless tread machines. No sprockets 25 whatever are required in connection with the chains 10 and only a driving sprocket is necessary in connection with each of the chains 10a, providing a structure which is less expensive and at the same time superior. The grooved tracks 16 30 and 19 effectively guide the chains and transmit weight thereto and the chains effectively guard said tracks to prevent pieces of rock and the like from falling and accumulating thereon.

The general construction shown and described, 35 may be followed if desired, but within the scope of the invention as claimed, numerous variations may be made.

I claim:—

1. In a mobile machine supporting means, an 40 endless tread chain having longitudinal side links, additional longitudinal links between the sides of the chain, transverse rollers between said side links and said additional links, and tread plates secured to at least some of said links; and a load- 45 supporting chain-guiding track having a horizontal portion resting on the rollers of the lower reach of said chain, said track having at least one curved end occupying a bight portion of the chain and engaging the rollers thereof, said track being 50 straddled by the inner edges of said side links and being peripherally grooved to receive the inner edges of said additional links.

2. In a mobile machine supporting means, an 55 endless tread chain having longitudinal side links, additional longitudinal links between the sides of the chain, transverse rollers between said side links and said additional links, and tread plates secured to at least some of said links; and a load- 60 supporting chain-guiding track having a continuous edge engaged by the rollers of said chain, said continuous track edge being straddled by the inner edges of said side links and being peripherally grooved to receive the inner edges of said additional links.

3. In a mobile machine supporting means, an 65 endless tread chain having transverse rollers, means for supporting a portion of the machine frame upon the lower reach of said chain, including a driven sprocket and a track engaging the 70 chain rollers, said track having an uninterrupted edge of a length to simultaneously engage substantially all rollers of the chain not engaged by said sprocket; said chain having side links and additional links between the sides of the chain, 75

and tread plates secured to at least some of the links; the inner edges of said side links being disposed astride said track edge, said track edge being grooved to receive the inner edges of said

5 additional links.

4. In a mobile machine supporting means, an endless tread chain comprising longitudinal side links, additional longitudinal links between the

sides of the chain, transverse rollers between said side links and said additional links, and tread plates secured to at least some of the links, said rollers being of a diameter less than the width of said side and additional links, whereby the 5 links project beyond the peripheries of the rollers for track-engaging purposes.

BENJAMIN H. FLYNN.
